GAS LIFT APPARATUS

Robert G. Nisle and Fred H. Poettmann, Bartlesville, Okla., assignors to Phillips Petroleum Company, a corporation of Delaware

Application June 23, 1952, Serial No. 294,986

16 Claims. (Cl. 103—232)

1

This invention relates to gas lift apparatus, particularly for controlling the rate of flow of pressurized gas into gas lift wells.

In gas lift operations, gas is introduced into the interspace between the tubing and casing of a well. The pressurized gas thereby introduced aerates the oil and causes it to flow upwardly through the tubing to the surface of the well. In such systems, the tubing advantageously extends a short distance below the level of the oil being produced, or alternatively, the tubing is perforated adjacent the upper level of the oil to be produced.

In starting the gas lift operation, the pressure in the interspace is initially sufficiently high as to force the oil upwardly through the tubing. As the operation begins, alternate pressure drops and pressure rises occur until the pressure reaches an operating value substantially lower than the initial pressure, at which time operation is stabilized. A similar pressure fluctuation is observed when a well "dies" due to a change in the operating conditions of the system. When the conditions change in such manner that the gas input rate is insufficient to maintain flow, the level of the oil in the well rises above the lower end of the tubing or, alternatively, the upper end of the perforated portion of the tubing. Thereupon, the pressure in the well increases since no gas can pass upwardly through the tubing under these conditions. The pressure increases until the oil level is depressed below the bottom of the tubing or, alternatively, below the perforated portion of the tubing at which time gas will be vented out through the tubing and the pressure in the interspace between the tubing and casing drops until the liquid level again rises to close off the bottom of the tubing. Successive pressure fluctuations of this type occur with increasingly greater amplitude until the well ceases to flow, at which time the pressure in the interspace is at a high value above the normal operating pressure but below the initial pressure required to start operation of the well.

It has been previously proposed to control the gas input to a gas lift well in such fashion that less gas is admitted when the well pressure decreases and more gas is fed automatically to the well as the pressure increases, the advantage being that gas is conserved in that no more than the amount required to maintain flow is supplied to the well at any time.

In service, wells are periodically visited by a pumper who makes periodic checks of well operation. Inasmuch as both pressure rises and pres-

2

sure drops are characteristic of a "dying" well, in accordance with this invention, the rate of flow of gas is increased whenever there is either an excessive drop or an excessive rise in pressure. In this manner, consistent operation is maintained so long as the system operates in stable fashion without excessive pressure fluctuations. Although slightly more gas may be required under certain conditions, the cost of the additional gas is more than offset by the stable operation obtained and positive prevention of production stoppage. If a higher than normal amount of gas is consumed during a period of automatic operation, the condition of the well can be checked by the pumper at the next inspection and corrective steps taken.

It is an object of the invention to provide automatic control means for a gas lift pumping system that preferably prevents the stopping of production under many adverse operating conditions.

It is a further object to provide a gas lift pumping system which is reliable in operation and which can be added to existing pumping equipment with little expenditure of time or material.

Various other advantages, objects and features of the invention will become apparent from the following detailed description taken in conjunction with the accompanying drawings, in which:

Figure 1 is a perspective view of the gas lift apparatus of this invention;

Figures 2 and 3 are graphs illustrating the operation of a gas lift pumping system;

Figure 4 is a vertical sectional view, partially in elevation, of the pressure-responsive device of Figure 1;

Figure 5 is a perspective view of a modified form of control apparatus for a gas lift system;

Figure 6 is a vertical sectional view, partially in elevation, of a still further modified control system;

Figure 7 is a sectional view taken along the lines 7—7 of Figure 6 looking in the direction of the arrows; and

Figure 8 is a detail view of a portion of Figure 6.

Referring now to Figures 2 and 3, Figure 2 illustrates pressure variations which occur when operation of the gas lift well is initiated. It will be noted that the pressure in the interspace between the tubing and casing first rises to an initial "kick-off" pressure at which flow is initiated. Thereafter, the pressure fluctuates about the line labeled "operating pressure," the fluctuations becoming of progressively decreasing amplitude until stable conditions are reached at the operating pressure. Figure 3 illustrates the conditions

observed when a well "dies," that is, ceases to produce. It will be noted that pressure variations of progressively increasing amplitude occur about the line labeled "operating pressure" due to the rise and fall of the oil level in the well, as previously explained. When production stops, the pressure reaches a stable value intermediate the "kick-off" pressure and the "operating" pressure. It will be noted, therefore, that both increases and decreases in pressure relative to the line labeled "operating pressure" are characteristic of an unstable gas lift operation which, if not checked, will cause the well to stop flowing. In accordance with this invention, whenever such fluctuations in pressure appear, whether they are increases in pressure or decreases in pressure, the rate of flow of gas is progressively increased until stable operation is again attained.

In Figure 1, we have shown a well having casing 10 and tubing 11, the tubing extending through a casinghead 12 to an outlet pipe 13, and having perforations 14 formed therein adjacent the level of the oil being produced. Alternatively, it will be understood that the tubing may be imperforate and extend to a region just below the level of the oil. In order to obtain gas lift production, gas is fed to the interspace or annulus 15 between the tubing and casing through a gas input line 16, the gas aerating the oil and lifting it to the surface through the tubing 11.

Operatively associated with the input line 16 is a rate of flow controller 17 which includes a flow-sensing device 18 and a valve 19 which is opened or closed automatically to provide a rate of flow as determined by the setting of the controller. Controller 17 can be of any suitable type, and preferably has a pointer which is manually set to the desired rate of flow, this pointer being moved by a flexible cable in the manner hereinafter described to control the gas lift operation. The setting, in turn, is controlled by mechanism 20 including a pressure-sensing device 21 responsive to the pressure in the interspace 15 adjacent the surface of the well. The operation of mechanism 20 is such that either a predetermined increase or a predetermined decrease in the pressure within the interspace adjacent device 21 causes a stepwise increase in the setting of rate of flow controller 17 which produces a predetermined increase in the rate of flow of gas to the well. Each time the flow is increased, there is a possibility that operation of the well will become stable at the new gas input rate. If such stable operation occurs, no further action of the controller is caused. However, if an increment in the flow rate does not produce stable conditions, further fluctuations will produce additional increments in the flow rate as necessary until stable operation is obtained.

It will be noted that the pressure responsive device 21 includes a laterally protruding cylindrical casing 22, Figures 1 and 4, within which is mounted a bellows 23 exposed to the pressure existing within the interspace 15. The bellows has secured thereto a rod 24 which extends through a housing 25 and is pivoted to an arm 26 which, in turn, is pivoted to a link 27. The position of link 27, therefore, is representative of the pressure existing within the interspace 15 adjacent the surface of the well.

The rectilinear movement of link 27 is transmitted to a lever 28 pivoted at 29 to a support 30, this lever carrying a set of contacts 31, 32. Co-operating with the contacts 31, 32 are contacts 33 and 34, respectively, which are secured to

contact arms depending from a member or assembly 35 also pivoted at 29 to the support 30. Both contacts 33, 34 are connected in circuit with a winding 36 of a solenoid-actuated ratchet mechanism 37, a current source, not shown, and the contacts 31, 32 carried by the lever 28. When this circuit is closed by engagement of contacts 31, 33, or 32, 34, the solenoid winding 36 is energized and a pawl 38 produces a stepwise movement of a ratchet wheel 39. The position of ratchet wheel 39 is transmitted by a flexible cable 40 to the flow controller 17 in such fashion that the position of the ratchet wheel controls the position of the "set" pointer of the controller and, hence, the rate of flow of gas through input line 16. The movement of link 27 is also transmitted to a lever 43, one end 44 of which is pivoted to link 27 and the other end 45 of which is supported by springs 46, 47 secured to a mounting bracket 48. A lever 49 is pivoted at 50 to the lever 43, one end of the lever 49 being secured to a dash pot 51 and the other end of lever 49 being connected by links 52 and 53 with the pivoted member 35 so that the position of the contacts 33, 34 is controlled by the position of lever 49.

In operation, assuming that the well is operating normally and the operating pressure is stable, contacts 31, 32 are positioned between and out of engagement with contacts 33, 34 with the result that ratchet mechanism 37 is deenergized and rate of flow controller causes a proper amount of gas to be supplied to the well to maintain equilibrium conditions. Should an operating variable of the system change so as to cause unstable operation of the well, the operating pressure begins to fluctuate in the manner shown by Figure 3. Assuming that the first fluctuation produces a pressure increase, the resulting movement of link 27 responsive thereto causes lever 28 to move in a counterclockwise direction, Figure 1. If the increase is of greater than a predetermined extent represented by the initial spacing between contacts 31, 33, these contacts are closed with the result that ratchet mechanism 37 is energized to cause one stepwise movement of ratchet wheel 39 with a resultant increase in the setting of the controller 17 and increased rate of flow of gas through line 16.

The described movement of link 27 also produces rightward movement, Figure 1, of the lower end 44 of lever 43. This rapid movement cannot be followed at pivot point 50 due to the dash pot 51 which resists any abrupt change in the lateral position of pivot point 50. As a result, lever 43 pivots about point 50 in a counterclockwise direction, thereby storing energy in the springs 46, 47 which thereupon tend to restore the end 45 to its original position. The energy thus stored in the springs 46, 47 produces a slow clockwise pivoting of lever 43 about pivot point 44 at a rate determined by the dash pot 51. As a result a slow leftward movement of lever 49 occurs which, by the action of links 52 and 53, causes a counterclockwise movement of member 35 and the contacts 33, 34. That is, the initial counterclockwise movement of lever 28 is followed by a slower corresponding counterclockwise movement of member 35. If stable conditions are obtained as a result of the described single actuation of ratchet mechanism 37, the contacts 31, 32 remain positioned intermediate the fixed contacts 33, 34 and no further corrective action takes place. However, should the pressure increase continue, a further counterclockwise movement of lever 28 occurs resulting in a second closure of contacts

31, 33 which, in turn, energizes ratchet mechanism 31 and produces an additional stepwise increase in the rate of flow through gas input line 16. This second movement of lever 28 is followed by a second slow shifting of member 35 in the same direction due to the action of the springs 46, 47 and dash pot 51. Successive cycles of operation occur in the described manner until a stable condition is reached at which time contacts 31, 32 rest between the contacts 33, 34 without engaging them.

If the initial unstable condition results in a decrease in pressure within interspace 15, a leftward rectilinear movement of link 27 results and lever 28 is moved in a clockwise direction. If the extent of this movement is greater than the initial spacing between contacts 32, 34, there is an actuation of ratchet mechanism 31 and an increase in the gas flow rate as a result of resetting controller 17. The described rightward movement of link 27 produces a slow clockwise following movement of member 35 due to the action of springs 46, 47 and dash pot 51 so that, if the original increase in flow rate does not result in stable operation, there is a second closure of contacts 32, 34 and a further increase in the gas input rate. Such cycles continue until stable operation of the system is attained.

It will be evident, therefore, that either an increase or decrease in pressure of greater than a predetermined extent represented by the initial spacing between contacts 31, 33 and 32, 34 results in stepwise increases in the rate of flow of gas through line 16, such stepwise increases continuing until stable operation is resumed. The flow rate is checked by the operator at each inspection, and the operator can take steps to correct any conditions leading to the unstable operation corrected by the automatic operation of the control system which resulted in an increased or greater than normal rate of flow of gas through the line 16.

In Figure 5, we have shown a system wherein the levers and pivots of Figure 1 are replaced by gearing. In this structure, the link 27 of Figure 1 is connected to a rack 55 which is shifted longitudinally in accordance with changes in pressure within the interspace 15. Rack 55 drives a spur gear 56 carrying a lever 57 and contacts 58, 59 corresponding to the lever 28 and contacts 31, 32 of Figure 1. Rack 55 also drives a spur gear 60 which is connected by gear 61 to a shaft 62 coupled to a gear 63 of a differential mechanism 64. The mechanism 64 also includes a gear 65 to which are secured springs 66 and 67 tending to bias a shaft 68 carrying gear 65 to a predetermined angular position. The mechanism 64 further includes a ring gear 69 within which is carried a pair of pinions 70 and 71 meshing with the gears 63, 65. Rotation of the ring gear is transmitted through gearing 72 to a shaft 73. At the upper end of shaft 73 is a spur gear 74 meshing with a rack 75 which is operatively connected to a dash pot 76. Rotary movement of shaft 73 is also transmitted through gearing 77 and 78 to a member 79 carrying contacts 80 and 81 cooperating with the contacts 58 and 59, respectively. Rotation of shaft 73 produces a clockwise or counterclockwise movement of member 79 depending upon the direction of shaft rotation. The contacts 58, 80 and 59, 81 are connected in circuit with the solenoid actuated ratchet mechanism 31 and rate of flow controller 17 in the manner described in connection with Figure 1.

It will be apparent that the lever 57 moves in a

counterclockwise or clockwise direction responsive to increases or decreases in pressure in the manner explained in connection with the lever 28 of Figure 1. Movement of the lever 57 in either direction is followed by a slow corresponding movement of the member 79 so that successive increases in gas flow rate are made until a stable condition is reached. For example, it will be noted that a rightward movement, Figure 5, of rack 55 produces a counterclockwise movement of lever 57. Such movement of the rack is transmitted to gear 63 of differential mechanism 64 and, as shaft 73 cannot move rapidly due to its connection to dash pot 76, the motion of shaft 62 is transmitted to gear 65 and shaft 68 which rotates in a reverse direction and stores energy in springs 66 and 67. These springs cause shaft 68 to slowly move back toward its original position with resultant rotation of shaft 73 and gear 69 at a rate determined by the dash pot 76. This slow rotation of shaft 73 is transmitted through gearing 77, 78 to member 79 and produces a slow counterclockwise movement thereof in the same direction as the movement of lever 57. It will be evident that a leftward movement of the rack 55 produces a clockwise movement of lever 57 and a slow following clockwise movement of member 79 due to the action of springs 66, 67 and dash pot 76. Hence, the system functions in the same manner as the system of Figure 1 except that the pivots, links, and levers are replaced by gears and shafts, which are more suitable in certain applications.

In Figures 6, 7, and 8, we have shown a system wherein the electrically-actuated ratchet mechanism is replaced by a pneumatically actuated ratchet mechanism, thereby permitting the control device to be used at well locations where electric current is not available. In this modification, the link 27 of Figure 1 is connected to a rack 85 meshing with teeth formed on a disk 86. Formed in the disk 86 is a nozzle 87 to which instrument air or other gas under pressure is fed through a line 88. Slidably mounted outside the disk 86 is a sector-shaped member 89 which carries a pair of communicating ports 90 and 91, both ports communicating with a passage 92 leading to an outlet line 93. The angular position of sector-shaped member 89 is controlled by a rack 94 meshing with teeth formed on the outer surface of sector-shaped member 89. Outlet line 93 leads to a piston chamber 95 having a piston rod 96 protruding therefrom which is connected by a lever 97 pivoted at 98 to a support 99. Also pivoted to the lever 97 is a pawl 100 which cooperates with a ratchet wheel 101.

In operation, ratchet wheel 101 is mechanically connected to the set pointer of unit 17 as in Figure 1, so that the setting of the controller is dependent upon the angular position of the ratchet wheel. Rack 94 is connected to a suitable dash pot and spring mechanism of the character described in Figures 1 and 5 so as to produce a slow angular movement of sector-shaped member 89 in the same direction as movements of disk 86 caused by pressure changes in the interspace 15. For example, rack 85 can be connected to the pivot point 44 of lever 43 of Figure 1, and rack 94 can be connected to the lever 49 of Figure 1.

In this modification, an increase in pressure causes a rightward movement, Figure 6, of rack 85 and a counterclockwise movement of disk 86. If this movement is of sufficient extent as to cause nozzle 87 to register with port 90, air under

pressure is fed through line 93 to piston chamber 95 with the result that a stepwise movement of ratchet wheel 101 is produced by pawl 100. Thereafter, port 90 moves slowly in a leftward direction, Figure 6, so that the nozzle 87 is once more positioned intermediate the ports 90, 91 and no air is transmitted to piston chamber 95. If the increase in gas flow rate caused by the described movement of ratchet wheel 101 produces stable operation, no further operation of the system occurs. However, if there is a further increase in pressure, a further counterclockwise movement of disk 86 occurs and the system passes through another corrective cycle. It will be evident that a decrease in pressure produces a clockwise movement of disk 86 which causes operation of the ratchet wheel and flow controller if the pressure change producing rotation of the disk is of sufficient magnitude as to cause nozzle 87 to register with port 91. Further, responsive to such clockwise rotation of the disk 86, there is a slow clockwise movement of sector-shaped member 89 so that the apparatus is in readiness for a new cycle of operation if stable operation is not caused by the initial operation of the ratchet mechanism and flow controller.

While the invention has been described in connection with a present, preferred embodiment thereof, it is to be understood that this description is illustrative only and is not intended to limit the invention.

We claim:

1. In gas lift apparatus for a system wherein gas is introduced into the interspace between the tubing and casing of a well through a gas input line, and oil is aerated and lifted through the tubing by such gas, in combination, a pressure-responsive device having a sensing element in said interspace adjacent the surface of the well and producing an output representative of pressure in said interspace, a rate of flow controller in said line determining the rate of flow of pressurized gas into said interspace, and mechanism operatively connected to said controller and responsive to the output of said device, said mechanism actuating said controller so as to increase the rate of flow of gas responsive both to a predetermined increase and a predetermined decrease in the pressure represented by the output of said device.

2. In gas lift apparatus for a system wherein gas is introduced into the interspace between the tubing and casing of a well, and oil is aerated and lifted through the tubing by such gas, in combination, means for producing an output representative of the pressure in said interspace, and mechanism controlled by said last-named means to increase the rate of flow of gas into said interspace responsive both to a predetermined increase and a predetermined decrease in the output of said pressure-responsive means.

3. In gas lift apparatus for a system wherein gas is introduced into the interspace between the tubing and casing of a well through a gas input line, and oil is aerated and lifted through the tubing by such gas, in combination, a rate of flow controller in said gas input line, a pressure-responsive device producing an output proportional to the pressure in said interspace, and control mechanism operatively connected to said rate of flow controller and responsive to the output of said pressure-responsive device, said mechanism including means for establishing an initial maximum allowable pressure above the normal operating pressure in said interspace, means for

establishing an initial minimum allowable operating pressure below the normal operating pressure, and means for operating said controller so as to increase the rate of flow of gas into said interspace when the pressure rises above said maximum allowable value or falls below said minimum allowable value.

4. In gas lift apparatus for a system wherein gas is introduced into the interspace between the tubing and casing of a well through a gas input line, and oil is aerated and lifted through the tubing by such gas, in combination, a rate of flow controller in said gas input line, a pressure-responsive device producing an output proportional to the pressure in said interspace adjacent the surface of the wall, and control mechanism operatively connected to said rate of flow controller and responsive to the output of said pressure-responsive device, said mechanism including means for establishing an initial maximum allowable pressure above the normal operating pressure in said interspace, means for establishing an initial minimum allowable operating pressure below the normal operating pressure, means for operating said controller so as to increase the rate of flow of gas into said interspace when the pressure rises above said maximum allowable value or falls below said minimum allowable value, and means responsive to such rise or fall of pressure to reset said initial maximum value and said initial minimum value to new values which are different from the initial values by an amount corresponding to the pressure increase or decrease.

5. In gas lift apparatus for a system wherein gas is introduced into the interspace between the tubing and casing of a well, and oil is aerated and lifted through the tubing by such gas, in combination, a pressure-responsive device communicating with the interspace between the tubing and casing adjacent the surface of the well, said device including a movable member whose position is representative of said pressure, means cooperating with said member and actuatable upon a predetermined movement thereof either in a direction representing a pressure increase or in a direction representing a pressure decrease, means controlling said cooperating means to cause it to follow the movement of said member, said last-mentioned means including a damper, whereby the following movement of the cooperating means is slower than the corresponding movement of said member, and means responsive to the actuation of said cooperating means to increase the rate of flow of gas into said well by a predetermined amount.

6. In gas lift apparatus for a system wherein gas is introduced into the interspace between the tubing and casing of a well, and oil is aerated and lifted through the tubing by such gas, in combination, a pressure-responsive device communicating with the interspace between the tubing and casing, said device including a movable member whose position is representative of said pressure, means cooperating with said member and actuatable upon a predetermined movement thereof either in a direction representing a pressure increase or in a direction representing a pressure decrease, means controlling said cooperating means to cause it to follow the movement of said member, said last-mentioned means including a dash pot operatively connected to said cooperating means, a spring, means responsive to movement of said member to store energy in said spring, means for releasing the energy stored in

said spring so as to move said cooperating means at a speed determined by said dash pot, whereby the following movement of the cooperating means is slower than the corresponding movement of said member, and means responsive to each actuation of said cooperating means to increase the rate of flow of gas into said well by a predetermined amount.

7. In gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing, said device including a movable member whose position is representative of said pressure, means cooperating with said member and actuatable upon a predetermined movement thereof either in a direction representing a pressure increase or in a direction representing a pressure decrease, means controlling said cooperating means to cause it to follow the movement of said member, said last-mentioned means including a damper, whereby the following movement of the cooperating means is slower than the corresponding movement of said member, a rate of flow controller operatively connected to said gas input line, and pawl and ratchet means responsive to each actuation of said cooperating means to increase the setting of said rate of flow controller and thereby the gas input rate in a stepwise manner.

8. In a gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing adjacent the surface of the well, said device including a movable member whose position is representative of said pressure, means cooperating with said member and actuatable upon a predetermined movement thereof either in a direction representing a pressure increase or in a direction representing a pressure decrease, means controlling said cooperating means to cause it to follow the movement of said member, said last-mentioned means including a dash pot operatively connected to said cooperating means, a spring, means responsive to movement of said member to store energy in said spring, means for releasing the energy stored in said spring so as to move said cooperating means at a speed determined by said dash pot, whereby the following movement of the cooperating means is slower than the corresponding movement of said member, a rate of flow controller operatively connected to said gas input line, and pawl and ratchet means responsive to each actuation of said cooperating means to increase the setting of said rate of flow controller and thereby the gas input rate in a stepwise manner.

9. In gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing adjacent the surface of the well, said device including a lever whose position is representative of said pressure, said lever carrying a pair of electrical contacts, a movable pair of contacts cooperating with the contacts on said lever and actuatable upon a

predetermined movement thereof either in a direction representing a pressure increase or in a direction representing a pressure decrease, a rate of flow controller operatively connected with said gas input line, solenoid operated ratchet mechanism actuatable to increase the setting of said controller in a stepwise manner so as to increase the rate of flow of gas, and a circuit including a current source, said solenoid, said lever and said movable contacts, said circuit being arranged to actuate said solenoid mechanism each time the lever engages one of said contacts.

10. In gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing, said device including a lever whose position is representative of said pressure, said lever carrying a pair of contacts, a pivoted member carrying a pair of contacts cooperating with contacts on said lever, one set of contacts being closed upon a predetermined movement of said lever in a direction representing a pressure increase, and the other set of contacts being closed upon a predetermined movement of said lever in a direction representing a pressure decrease, means controlling said pivoted member to cause it to follow the movement of said lever at a slower rate than the corresponding movement of said lever, said controlling means including a spring, means responsive to movement of said lever for storing energy in said spring, a dash pot operatively connected to said pivoted member, means for imparting the energy of said spring to said pivoted member at a rate determined by said dash pot so as to effect said following movement of the pivoted member, a rate of flow controller operatively connected in said gas input line, solenoid operated ratchet mechanism to increase the setting of said controller in a stepwise manner responsive to each solenoid actuation, and a solenoid-actuating circuit including said solenoid, a current source, said lever contacts, and the contacts on said pivoted member, said circuit being closed upon each engagement of either of said sets of contacts.

11. In gas lift apparatus for a system wherein gas is introduced into the interspace between the tubing and casing of a well through a gas input line, and oil is aerated and lifted through the tubing by such gas, in combination, a bellows communicating with the interspace between the tubing and casing adjacent the surface of the well, a pivoted lever bearing a pair of contacts, a link connecting said bellows to said lever, an arm pivoted to said link, a spring assembly connected to said arm in such fashion that movement of the arm in either direction stores energy in said springs and tends to return said arm to its original position, a rod pivoted upon said arm, a dash pot connected to one end of said rod, a pivoted movable contact assembly secured to the other end of said rod, said assembly including a pair of contacts cooperating with the contact set upon said lever, solenoid-actuated ratchet mechanism having a solenoid winding connected in circuit with both contacts of said assembly and the contact set of said lever, a rate of flow controller in said gas input line, and means for transmitting rotation of the ratchet to said controller so as to vary the setting thereof.

12. In gas lift apparatus for a system wherein

11

gas is introduced into the interspace between the tubing and casing of a well through a gas input line, and oil is aerated and lifted through the tubing by such gas, in combination, a bellows communicating with the interspace between the tubing and casing adjacent the surface of the well, a rack movable by said bellows, a lever bearing a pair of contacts movable by said rack, differential gear mechanism having three members, one member being geared to said rack, a spring assembly connected to another member of said differential gear mechanism in such fashion that movement of said last-mentioned member in either direction stores energy in said springs and tends to return said member to its original position, a dash pot geared to a third member of said differential gear, a pivoted movable contact assembly geared to said third member, said assembly the contact set upon said lever, solenoid-actuated ratchet mechanism having a solenoid winding connected in circuit with both contacts of said assembly and the contact pair on said lever, a rate of flow controller in said gas input line, and means for transmitting rotation of the ratchet to said controller so as to vary the setting thereof.

13. In gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing adjacent the surface of the well, said device including a movable member whose position is representative of said pressure, a rotatable nozzle whose position is controlled by said member, a pivoted assembly having a pair of ports cooperating with said nozzle so that communication is established between one of said ports and said nozzle upon a predetermined movement of the nozzle in either direction, means for supplying fluid under pressure to said nozzle, a rate of flow controller in said gas input line, and pneumatically-operated ratchet mechanism actuatable to increase the setting of said controller in a stepwise manner so as to effect an increase in the rate of flow of gas, said ratchet mechanism being pneumatically connected to both of said ports so as to be actuated when said nozzle registers with either port.

14. In gas lift apparatus for a system wherein gas is introduced into the interspace between the tubing and casing of a well through a gas input line, and oil is aerated and lifted through the tubing by such gas, in combination, a pressure-responsive device communicating with the interspace between the tubing and casing adjacent the surface of the well, said device including a movable member whose position is representative of said pressure, a rotatable nozzle whose position is controlled by said member, a pivoted assembly having a pair of ports cooperating with said nozzle so that communication is established between one of said ports and said nozzle upon a predetermined movement of the nozzle in either direction, means for causing said pivoted assembly to follow the movement of said nozzle, said last-mentioned means including a damper con-

12

structed and arranged to slow down said following movement of the pivoted assembly, means for supplying fluid under pressure to said nozzle, a rate of flow controller in said gas input line, and pneumatically-operated ratchet mechanism actuatable to increase the setting of said controller in a stepwise manner so as to effect an increase in the rate of flow of gas, said ratchet mechanism being pneumatically connected with both of said ports so as to be actuated when said nozzle registers with either port.

15. In gas lift apparatus for a system wherein gas is introduced into the interspace between the tubing and casing of a well through a gas input line, and oil is aerated and lifted through the tubing by such gas, in combination, a bellows communicating with the interspace between the tubing and casing adjacent the surface of the well, a rack movable by said bellows, a rotatable nozzle, the position of which is determined by the position of said rack, a cooperating rotatable member including a pair of ports which register with said nozzle upon a predetermined movement thereof in either direction, means controlling said cooperating means to cause it to follow the movement of said nozzle, said last-mentioned means including a damper, whereby the following movement of the cooperating means is slower than the corresponding movement of said nozzle, a rate of flow controller in said gas input line, and pneumatically-operated ratchet mechanism actuatable to increase the flow setting of the controller in a stepwise manner, means for supplying air under pressure to said nozzle, and means for effecting communication between both ports and said pneumatically-actuated ratchet mechanism.

16. In gas lift apparatus for a system wherein gas is introduced into the interspace between the tubing and casing of a well through a gas input line, and oil is aerated and lifted through the tubing by such gas, in combination, a bellows communicating with the interspace between the tubing and casing adjacent the surface of the well, a rack movable by said bellows, a rotatable nozzle, the position of which is determined by the position of said rack, a cooperating rotatable member including a pair of ports which register with said nozzle upon a predetermined movement thereof in either direction, means controlling said cooperating means to cause it to follow the movement of said nozzle, said last-mentioned means including a differential mechanism having a first gear member geared to said rack, a second gear member geared to said cooperating rotatable member, and a third member, means biasing said third member to a predetermined angular position, and a dash pot operatively connected to said second member, a rate of flow controller in said gas input line, and pneumatically-operated ratchet mechanism actuatable to increase the flow setting of the controller in a stepwise manner, means for supplying air under pressure to said nozzle, and means for effecting communication between both ports and said pneumatically-actuated ratchet mechanism.
